Patented June 13, 1916.

UNITED STATES PATENT OFFICE.

PERRY E. TAYLOR, OF CHANUTE, KANSAS.

ELECTRIC-FAN DEFLECTOR.

1,187,400.

Specification of Letters Patent. Patented June 13, 1916.

Application filed November 16, 1914. Serial No. 872,416.

To all whom it may concern:

Be it known that I, PERRY E. TAYLOR, a citizen of the United States of America, and resident of Chanute, in the county of Neosho and State of Kansas, have invented certain new and useful Improvements in Electric-Fan Deflectors, of which the following is a specification.

This invention relates to fans and particularly to means for deflecting air currents created by the fan to disperse or concentrate the said air currents according to the requirements in practice, and the invention is particularly designed for insuring equal distribution of the air currents in a room to be ventilated.

A further object of this invention is to provide an air deflecting device of the character indicated having novel means for attachment to a fan guard that the said deflecting means may be carried by the guard regardless of whether the guard is on an oscillating or a stationary fan.

A still further object of this invention is to provide current deflecting means having novel means for retaining the deflecting means at different positions of adjustment with relation to the guard and with relation to each other.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, and in

which—

Figure 1 illustrates a view in elevation of a fan embodying the invention; Fig. 2 illustrates a detail sectional view of a fragment of the deflecting means, a fragment of a fan, and a fragment of a guard; Fig. 3 illustrates a plan view of a guard and the deflecting means applied thereto; Fig. 4 illustrates a view in elevation of one of the deflecting means; and Fig. 5 illustrates a deflecting

blade of curved formation.

In these drawings 6 denotes the base of a fan, 7 the fan blades and 8 a guard and as these parts or elements may be of any appropriate or ordinary construction, they are not described in detail.

The deflecting means which comprises the subject matter of the invention consists in a frame formed as here shown of vertically and horizontally disposed rods 9 and 10, the said vertically disposed rods crossing the horizontally disposed rods and secured to them at their juncture by a welding process to produce a framelike structure for supporting the deflecting blades 11 and 12.

As shown in the drawing, the horizontally and vertically disposed rods may be bent to be interwoven or interlocked with the wire structure of the frame or guard 8, thus making it possible to readily apply and remove the deflector supports to fans of ordinary construction or to or from the guards thereof.

The deflecting members 11 and 12 each have ears 15 bent to form eyes to receive the vertically disposed rods 9 and as the upper ear 15 rests on the upper horizontally disposed rod 10, the blades are supported in proper position and are swingingly mounted on the said vertically disposed rods so that they may move to different angular relations to the front of the fan. It is apparent from the foregoing description and from an inspection of Fig. 3 of the drawings that the angles of the deflecting blades with relation to the guard or the fan determines the degree of distribution or concentration of the air currents according to the adjustment of the said blades. The blades are provided with means for holding them in different positions of adjustment, the said means consisting of a brace comprising the sections 16 and 16' having their outer ends connected by the pivot 17 and their inner ends connected by the pivots 18 to ears 19, it being understood that one ear 19 is carried by each of the blades. The sections 16 and 16' have pivoted joints 20 and 21 respectively, so that by breaking the joints, the length of the brace may be increased or diminished for the purpose of retaining the deflecting blades and greatly varying the positions at which the said blades are fastened or held for the purposes intended. As shown in the drawing, the ears 19 have angular portions 22 constituting bases which are fastened to the blades and, as stated, the braces are pivotally connected to the said ears.

The manner of applying the blade carrying rods to the guard or frame of an ordi-

nary fan is well illustrated in Figs. 1, 2 and 3, and further detailed description of the method or mode of operation is believed unnecessary.

- 5 It has been found in practice that by the device forming the subject matter of this invention, air currents may be diverted so as to distribute the current of air over a large area, and that by changing the angle of the 10 defectors or vanes, the width of the air current may be varied.

As shown in Fig. 5 of the drawing, the deflecting blade or vane 23 may be of curved formation and when of such construction, 15 the convexed sides of the blades are to be placed facing each other.

I claim—

1. In a deflector for air currents from fans, the combination with a fan frame, of 20 horizontally and vertically disposed rods crossing each other, said rods being secured at their points of intersection, the said bars being interlocked with the bars of the guard, deflector blades having ears oscillatingly 25 mounted on the said vertically disposed rods, said ears being in engagement with one of the horizontally disposed rods, whereby the blades are held against movement longitudinally of the said vertically disposed rod, and a brace for retaining the deflectors at 30 different positions of adjustment.

2. In a deflector for air currents from fans, the combination with a fan frame, of

horizontally and vertically disposed rods crossing each other, said rods being secured 35 at their points of intersection, the said bars being interlocked with the bars of the guard, deflector blades having ears oscillatingly mounted on the said vertically disposed rods, said ears being in engagement with one of 40 the horizontally disposed rods, whereby the blades are held against movement longitudinally of the said vertically disposed rod, a brace comprising pivotally connected sections, means for pivotally connecting the 45 braces to the blades whereby the said blades are held in different positions of adjustment.

3. In an attachment for fans, a frame, blades pivotally secured to the frame, means for connecting the blades together, said 50 means having pivoted joints whereby one of the blades may be moved without changing the position of the opposite blade.

4. In an attachment for fans, a frame, deflecting blades pivotally connected to the 55 frame, a brace member comprising sections pivotally connected together, the ends of the brace member being connected to the blades, whereby one of said blades may be moved independently of the other blade. 60

In testimony whereof, I hereunto affix my signature in the presence of two witnesses.

PERRY E. TAYLOR.
